UNITED STATES PATENT OFFICE.

WILLARD R. WALKER, OF SYRACUSE, NEW YORK

MECHANICAL DISHWASHER.

Application filed March 29, 1927. Serial No. 179,255.

This invention relates to a mechanical dishwasher involving the use of a vat or tub for receiving suitable open-work dish-supporting trays commonly used in washers 5 of this character together with a washing fluid which is impelled circumferentially and upwardly with a whirling motion through the open work trays and against the dishes therein by means of a rotary impeller located within the vat near the bottom 10 thereof and adapted to be driven by an electric motor or equivalent device.

In machines of this type one of the objects is to regulate the volume of water operated 15 upon so as to conserve the washing fluid and power required for circulating the same without sacrificing the washing efficiency of the machine and one of the specific purposes of the present machine is to carry forward 20 this main object to a more practical and economical degree than has heretofore been practiced.

Another object is to enable the entire vat 25 to be constructed of reasonably light sheet metal and to provide means whereby the gear case and motor may be supported upon the underside of the vat without overstraining any of the sheet metal parts to which they are connected.

30 A further object is to provide means for regulating the volume of water in the vat and for indicating the level thereof and also to provide means whereby the water may be drained from the vat and from the liquid 35 level indicator.

Another object is to provide means for supplying water to the interior of the vat 40 for washing and rinsing purposes and to locate the controls for the inflow and outflow of the water to and from the vat within 45 convenient reaching distance of the operator and preferably at one side of the vat near the top thereof where they are more or less protected from accidental operation by the top section of the vat.

Other objects and uses relating to specific parts of the machine will be brought out in the following description.

In the drawings:—

50 Figure 1 is a top plan partly broken away, of a mechanical dishwasher embodying the various features of my invention.

Figure 2 is a front elevation of the same, portions of the legs being broken away.

55 Figure 3 is an enlarged vertical sectional

view taken in the plane of line 3—3, Figure 1.

Figure 4 is an enlarged detail sectional view, partly broken away, taken on line 4—4, Figure 2.

As illustrated, this machine comprises a substantially cylindrical sheet metal tub or vat —1— having a circular sheet metal bottom section —2— and a sheet metal top —3—.

The lower and upper ends of the cylindrical section —1— are parallel and at right angles to the axis thereof, the lower end of said section being returned inwardly and upwardly for a short distance to form an annular groove for receiving the marginal edge of the bottom section —2—.

This bottom section —2— is provided with inner and outer frusto-conical portions —2'— and —2''— concentric with the axis of the cylindrical section —1— and arranged with their apices facing in opposite directions or upwardly and downwardly respectively, the central portion —2'— having its apex extended above the level of the outer marginal edge —2''— and its outer edges integrally united to the inner edges of the outer portion to form an annular trough —4— at the junctions of the two portions —2'— and —2''— for the reception and retention of a limited quantity of the washing fluid.

The marginal edge of the bottom section —2— is provided with a down-turned flange 5 seated in the annular groove in the lower end of the cylindrical section —1— wherein it is secured by any suitable fastening means such as screws —5— to form a liquid tight joint.

The central frusto-conical portion —2'— is provided with a central opening in its apex co-axial with the axis of the section —1— for receiving the upper reduced externally threaded end of an upwardly tapered shell of the case —6— having an annular flange —7— adapted to abut against the lower face of the walls of said opening, the reduced upper threaded end of said case being engaged by a cap nut —8— which also engages the upper face of the apex of the portion —2'— to firmly clamp the case section —6— to the apex of the bottom section —2— as shown more clearly in Figure 3.

The case section —6— is hollow and extends downwardly some distance below the

apex of the bottom section —2— for receiving and partially supporting the driving means for the impeller presently described.

An additional frusto-conical section 5 —9— is arranged concentric with the axis of the cylindrical section —1— to extend downwardly from the underside of the central frusto-conical portion —2'— of the bottom —2— with its apex facing downwardly and its marginal edges secured by slot welding or otherwise to the central frusto-conical portion —2'— near its junction with the outer frusto-conical portion —2''— as shown in Figure 2.

15 The section —9— is therefore co-axial with the axis of the cylindrical section —1— and is provided in its apex with a vertical opening to allow the case section —6— to pass therethrough.

20 The section —6— is provided with an annular flange —10— bolted or otherwise firmly secured to the underside of the apex of the section —9— which, being braced against the central frusto-conical portion 25 —2'— of the bottom —2— of the vat, serves also to brace the section —6— against lateral vibratory movement and assists in supporting said section —6— and parts carried thereby in operative position against 30 vertical movement.

The bottom of the trough 4 is provided with an outlet passage —11— at a lower level than the remaining portions of said bottom which inclines downwardly and circumferentially from a point in the trough 35 diametrically opposite to said outlet so that all of the water in the trough may be drained off at the outlet when desired.

The top section —3— of the vat is preferably rectangular in top plan and of greater width and depth from side to side and from front to rear than the diameter of the cylindrical section —1— and preferably consists of a sheet metal plate having the central portion of its main body open and depressed to form a circular flange —12—, the inner end of which is reduced to about the diameter of the interior of the cylindrical section —1— so as to fit snugly in the upper end 45 thereof, the portion of the flange just above the lower reduced end being increased in diameter to form an annular shoulder at —13— which is adapted to rest upon the upper edge of the cylindrical section —1— to hold 50 the top section —3— against undue downward movement and also to form a ledge for supporting an open-work basket of any well-known construction, not necessary to herein illustrate or describe, but which, with the 55 dishes therein, is adapted to be supported within the receptacle or cylindrical section —1— below the upper face of the top section —3—.

In like manner another open-work basket 60 or tray may be supported upon the marginal

edges of the bottom section —2— of the tub or vat.

The opposite sides and front of the top section —3— are provided with down-turned flanges —14— extending preferably below 70 the upper edge of the cylindrical section —1— while the rear edge of the top section —3— is bent upwardly to form a back portion —15— adapted to finish against a wall of the room but mainly to form a spatter-board to prevent splashing of water at the rear of the tub.

A suitable cover —16—, Figure 1, is supported in the open upper end of the tub section —3— to prevent escape of the washing fluid through the top of the vat during the washing operation.

Water level control and indicator.

A water supply pipe —17—, leading from any available source of water supply, extends from the back forwardly beneath the horizontal portion of the top —3— parallel with one of the side flanges —14— and between said side flange and the periphery of 90 the adjacent portion of the cylindrical section —1— to a point near the front corner of the top where it is connected to the upper end of an upper valve case —18— having its lower end connected by an elbow extension —19— to an inlet nozzle —20— in the adjacent side of the cylindrical section —1— for supplying water or other washing fluid to the interior of the vat.

The nozzle —20— is firmly secured in an 100 opening in the upright portion of the cylindrical section —1— intermediate its lower and upper end to form a water-tight joint therewith and also to allow the inflowing water to be used for rinsing purposes when 105 desired.

The valve case —18— is preferably located beneath the adjacent corner of the horizontal portion of the top —3— where it is more or less concealed and protected from 110 contact with external objects, said valve case being provided with any suitable valve operable at will through the medium of a handle —21— for controlling the flow of water into the vat.

The valve —18— and certain parts of other controls are further shielded and partially inclosed in a supplemental housing or shield-plate —22— having the upper end of its front portion offset forwardly and bolted 120 or otherwise secured to the front flange —14— of the top section —3— as shown in Figure 4.

The lower end of the plate —22— is offset 125 rearwardly and then upwardly to form a horizontal shelf —22'— and a rear upright flange —22''— for purposes presently described, the horizontal portion —22'— being provided with a vertical opening there-through for receiving the upper end of the 130

elbow extension —19— of the water supply pipe.

The valve case —18— is preferably located between the front and rear upright portions 5 of the shield or housing —22— and just above the bottom portion —22'— but the stem of its valve extends through an opening in the front upright portion of said housing and carries at its front the operating 10 handle —21— which is conveniently accessible to the operator when in a standing position.

It will be noted that the handle —21— is also directly beneath the horizontal portion 15 of one corner of the top —3— and at the rear of the vertical plane of the front flange —14— which enables the operator to work close to the front of the machine without liability of accidentally operating the valve 20 handle —21— and also serves to protect the other manually operated controls on said plate against contact with external objects from above.

That is, the upright portion of the shield 25 plate —22— is positioned some distance to the rear of the vertical plate of the front flange —14— of the top section —3— and constitutes what may be termed an instrument board for receiving and supporting the 30 valve handle —21— and other controlling handles presently described.

The means for controlling and indicating the level of the washing fluid in the vat or tub —1— comprises an upright shell or casing —23— located directly below the horizontal portion of one corner of the top section —3— at which the valve case —18— is positioned and in a plane some distance below said valve at about the level of the 40 bottom —2— of the vat, said casing —23— being provided with an inlet nipple —24— in a plane below the outlet —11— of said vat and operatively connected to said outlet by a conduit —25— which serves the 45 double purpose of a drainage outlet and also as a part of the level-regulating means.

The lower portion of the casing —23— is divided by an upright partition —26— into 50 separate upright compartments —27— and —28—, said partition being extended from side to side of the casing —23— and terminating at its upper end below the level of the gland —8— but above the level of the bottom 55 of the trough 4 to form an overflow passage —29— from the chamber —27— to the chamber —28— for limiting the volume of water in the vat to be acted upon by the impeller.

60 This partition —26— is provided with an opening —30— which, together with the inlet —24— are located in a plane some distance below the overflow passage —29— or top of the partition —26— and the outlet —11—, said casing —23— being also pro-

vided with a drainage outlet conduit —31— at the same level as or below the opening —30— to allow the water to be entirely drained from the vat through its outlet —11— when desired.

A tubular bushing —32— is tightly fitted in the opening —30— to form a seat for a butterfly valve —33— which is hinged at —34— to the top of the bushing —32— and is operatively connected to the lower 70 end of an upright rod —35—.

The upper end of this rod —35— is connected to a crank arm —36— on the rear end of a horizontal shaft —37— which is journaled in suitable bearings in the front 80 and rear upright portions of the shield plate —22— and has its front end provided with a handle —38— in front of the shield plate or instrument board —22— to be operated at will for opening and closing the 85 valve —33—.

A retracting spring —39— is operatively connected to the crank arm —36— to yieldingly hold the valve —33— and its operating parts in a closed position the valve being 90 hinged in such manner as to automatically close the direct passage for the water from the inlet —24— to the drainage pipe —31—.

A float —40— is mounted for vertical movement in the chamber —27— and is 95 adapted to normally rest upon suitable lugs —41—, Figure 4, in a plane below the overflow passage —29— when the water level in the tub is below the level of the overflow.

On the other hand, when the valve —33— is closed and the water level in the chamber —27— rises to or above the level of the overflow passage —29— the float —40— will 100 be automatically lifted by said rising water.

The float —40— is provided with an upwardly extending stem —42— having its upper end made of conducting material to constitute a movable electric switch member adapted to make contact with a pair of 110 terminals —43— of an electric circuit —44— which derives current from an external circuit —45— through the medium of a step-down transformer —46—.

A bell or equivalent signal —47— is connected in the circuit —44— to be operated when said circuit is closed by contact of the float rod —42— with the terminals —43—.

These terminals are mounted upon an insulating base —48— which is supported upon the lower horizontal portion —22'— of the instrument board —22— as shown in Figure 4 and through which the rod —42— is adapted to extend.

When water is being supplied to the interior of the vat by the opening of the valve —18— the drainage valve —33— will be closed thus permitting the water to rise in the chamber —27— thereby lifting the float —40— and causing the upper end of its 125

stem —42— to contact with the terminals —43— for closing the circuit through the bell signal —47—, the float —40— and terminals —43— being adjusted so that the signal 5 —47— will be operated at about the same time that the level of the liquid in the chamber —27— rises to the overflow passage —29— at which time any surplus water which may be introduced into the vat will 10 overflow into the chamber —28— around the closed valve —33— and out through the drainage pipe —31— which may be operatively connected to any suitable waste pipe not shown.

15 As soon as the signal —47— is operated the valve —18— in the supply pipe will be closed by the operator through the medium of the handle —21—.

On the other hand, when it is desired to 20 drain the water from the vat the valve —33— will be opened by proper adjustment of its operating member —38— thus permitting the water to pass through the opening —30— into the lower end of the chamber —28— and 25 thence outwardly through the drainage pipe —31—.

Impeller.

The means for circulating the washing 30 fluid circumferentially and upwardly with a whirling motion comprises in this instance a horizontal electric motor —49— mounted upon the bottom section —2— of the vat —1— and casing —6— and having its armature shaft operatively connected by gearing —50— to the lower end of an upright shaft —51— within the case —6—.

The lower end of the upright shaft —6— is stepped on an end-thrust bearing —52— 40 in the lower end of the case —6—, the upper end of said shaft being journaled in vertically alined openings in the upper end of said case and nut —8— to extend some distance above said nut.

45 A collar —53— of angular cross section is secured to the upper end of the shaft —51— directly over the nut —8— for receiving the hub —54— of a rotary impeller —55—.

50 That is, the hub —54— is closed at the top but is provided with a socket extending upwardly from its lower end and of angular cross section corresponding to the cross sectional form of the collar —53— whereby the 55 impeller may be placed upon and removed from the collar —53— by vertical sliding movement, the angular form of the collar and socket serving as spline connections between the shaft and impeller for transmitting rotary motion from the shaft to the impeller.

60 This impeller is provided with diametrically opposite downwardly diverging arms —56— corresponding to the incline of the 65 central cone portion —2'— of the bottom

—2— of the vat and adapted to travel in close proximity thereto.

The outer ends of these arms —56— are provided with impeller blades —57— which are preferably inclined downwardly in the 70 direction of rotation and are also arranged somewhat tangential to opposite sides of the hub for circulating the water circumferentially and at the same time throwing it upwardly with a more or less retarded centrifugal motion and with sufficient force to carry the water through the open-work dish-supporting trays and against the dishes therein with a glancing impact against the dishes.

80 The impeller blades —57— conform somewhat closely to the transverse contour of the bottom of the trough —4— and travel in close proximity thereto.

The outer end of the motor —49— is partially supported by a strap —58— which is secured to the adjacent portion of the marginal edge of the vat by one or more of the bolts —5—.

The inner end of the motor case —49— 90 is secured directly to and supported by the case —6— which, as previously described, is braced against lateral or vertical movement of its own conical form and also by the conical brace plate —9— on the underside 95 of the conical portion —2'— of the bottom —2— of the vat thus affording a simple and convenient means for supporting a motor and parts driven thereby against vibration.

The motor —47— may be connected in any well-known manner to a source of current supply not necessary to herein illustrate or describe except that the operating member as —59— of the motor-controlling switch 105 may be mounted directly upon the instrument board —22— adjacent the other manually-operated controls —21— and —38— thus permitting all of the controls to be adjusted by the operator while standing in 110 one position as, for example, at the front of the machine, all of said manually-operated controls being located at the rear of the vertical plane of the front flange —14— for purpose hereinbefore described.

Operation.

Assuming that the cover —16— of the vat is closed and that dish-supporting trays are placed within the vat in any well-known manner, then by opening the valve —18— water is allowed to flow into the vat and thence through the conduit —25— into the float chamber —27— (the valve —33— being closed) until the water level reaches the overflow passage —29— thereby lifting the float —49— from its seat —41— and causing the upper end of the float stem —42— to close the bell circuit across the terminals —43— for ringing the bell which indicates 130

that a sufficient quantity of water has entered the vat for washing purposes.

The motor-controlling switch —59— may then be operated to close the circuit through 5 the motor for operating the same and thereby cause the rotation of the impeller —55—.

This rotation of the impeller circulates the water in the trough —4— upwardly and circumferentially with a whirling motion 10 through the dish-supporting trays and against the dishes therein with sufficient force to thoroughly cleanse the same, this action being continued as long as may be desired or until the dishes are thoroughly 15 cleansed.

The valve —33— may then be opened by its operating member —38— to allow the water to drain off from the trough —4— through the drainage pipe —31— after 20 which the valve —33— may be again closed and the valve —18— re-opened to introduce rinsing water into the vat, it being understood that the valve —18— is to be closed as soon as the alarm —47— is operated.

25 This rinsing water may be circulated in the manner previously described by the rotation of the impeller —55— to rinse the dishes in the trays within the vat, either while the valve —18— is opened or after it 30 is closed.

Following this rinsing operation the valve —33— may be again opened to drain off the rinsing water from the vat.

The mechanism described is particularly 35 simple and efficient for dish-washing purposes but it is evident that various changes may be made in the detail construction without departing from the spirit of this invention.

40 What I claim is:—

1. In a mechanical dishwasher, a vat having its bottom formed of an inner frusto-conical portion and a surrounding inverted frusto-conical portion united to form an annular trough for the washing fluid, means for limiting the quantity of fluid in the trough to the level below the apex of the inner conical bottom portion and a rotary impeller having portions thereof movable in 45 said trough about the axis thereof.

2. In a mechanical dishwasher, a vat having its bottom provided with an annular trough for the washing fluid approximately midway between the periphery and the axis 50 of said vat, and a rotary impeller having portions thereof movable in said trough about said axis.

3. A mechanical dishwasher as in claim 2 in which means is provided for limiting the amount of fluid in said trough to a level below the portion of said bottom adjacent the axis of the vat.

4. A mechanical dishwasher as in claim 1 in which a conical reinforcing section has its 55 larger end secured to the underside of the

inner conical portion of the bottom of the vat co-axial therewith and its smaller end extended downwardly from the apex of the inner conical portion.

5. In a mechanical dishwasher, a vat having a central conical bottom portion arranged with its apex uppermost and provided with an opening therethrough, a gear case having its upper end secured in said opening to form a watertight joint therewith, an upright shaft extending through an opening in the upper end of the gear case and into the interior of the vat, an impeller operatively mounted on the upper end of the shaft within said vat to rotate with the shaft, 70 a motor attached to one side of the gear case and having its armature shaft extending through said side and gearing within the case for transmitting rotary motion from the armature shaft to the upright shaft. 75

6. A mechanical dishwasher as in claim 5 in which an inverted frusto-conical reinforcing section has its apex secured to the intermediate portion of the gear case and its larger end secured to the bottom of the vat 90 for bracing said gear case against vibratory movement.

7. In a mechanical dishwasher, a vat having its bottom provided with an upwardly projecting frusto-conical portion and an annular trough surrounding the base of said frusto-conical portion, said trough having an outlet, a conduit connected to the outlet and provided with an overflow above the level of the outlet and below the level of the apex of said frusto-conical portion for regulating the amount of water retained in the vat, and a rotary impeller having portions thereof movable in the trough for circulating the fluid circumferentially and upwardly. 95

8. In a mechanical dishwasher, a vat having its bottom provided with an upwardly projecting frusto-conical portion and an annular trough surrounding the base of said portion, a conduit connected to the trough 110 and provided with an overflow passage above the level of the trough and in a plane below the apex of said frusto-conical portion, a float in the conduit actuated by the rise of water therein to the level of the overflow, a 115 signal and means actuated by the float for causing the operation of the signal at about the time the water in the conduit reaches the level of the overflow.

9. In a mechanical dishwasher, a vat for receiving the washing fluid and dishes having its bottom provided with an annular trough substantially midway between its axis and periphery and concentric with said axis, an upright rotary shaft extending 120 through a central opening in the bottom of the vat, a rotary impeller mounted on the upper end of the shaft to rotate therewith within the trough, and means for limiting the amount of fluid in said trough to a level 125 130

below the shaft opening in the bottom of the vat.

10. In a mechanical dishwasher, a vat having its bottom provided with an upwardly tapered central portion and an upwardly flaring outer portion united to the base of the central portion to form an annular trough, an impeller rotatable in said trough, driving means for the impeller, a supporting member for the driving means flanged

against the underside of the apex of the central tapered portion, and a clamping member engaging the upper side of said apex and in screw engagement with the adjacent portion of the first-named member, one of said members being extended through an opening in said apex. 15

In witness whereof I have hereunto set my hand this 14th day of March, 1927.

WILLARD R. WALKER.
